UNITED STATES PATENT OFFICE.

JOHN P. WEIS, OF NYACK, NEW YORK, ASSIGNOR TO LUCIUS N. LITTAUER, OF GLOVERSVILLE, NEW YORK.

COMBINED TOP FEED AND RUFFLING MECHANISM FOR SEWING-MACHINES.

1,242,402.

Specification of Letters Patent.

Patented Oct. 9, 1917.

Application filed February 21, 1916. Serial No. 79,511.

To all whom it may concern:

Be it known that I, JOHN P. WEIS, a citizen of the United States, residing at Nyack, in the county of Rockland and State of New York, have invented certain new and useful Improvements in Combined Top Feed and Ruffling Mechanism for Sewing-Machines, of which the following is a specification.

This invention relates to sewing machines, the object of the invention being to provide a combined top ruffling and feeding mechanism in which each has a four-motion action, the top feed and ruffling mechanisms being so constructed and organized that the feeding stroke of either the ruffler blade or the top feed dog may be changed instantaneously one independently of the other or simultaneously so as to vary its action on the work; that is to say, the controlling means for each of these parts may be operated independently of the other, or they may be so connected as to operate together so that the feeding stroke of the top feed can be changed at the same time that the feeding stroke of the ruffling mechanism is changed, and this by the mere shifting of the foot treadle, so that the character of work may be controlled while the stitching proceeds.

An object of the improvement is to provide in a single machine practically three feeding mechanisms, a bottom feed acting on the material in front and rear of the needles, a top pull feed located in the rear of the needles, and a top ruffling mechanism located to act on the material in the front of the needles, together with a strip folder and hemming device or other attachment suited to the character of work to be produced.

A further object of the invention is the provision of a combined four-motion top ruffling and feeding mechanism comparatively simple in construction and efficient in operation, and which may be readily assembled with the several parts of a sewing machine.

This invention is particularly useful in connection with the joining of bibs to overalls, where a lining strip is stitched on the bottom to cover the raw edges and a hemmer is used to turn the edge of the overall while

the bib is stitched thereon. The ruffling mechanism assists in starting the work to the needles and overcomes the stretch, while the back top pull feed enables the machine to handle very heavy, bumpy, bulky work, as in the overall work described. There are places, as for instance on the fly, where some twelve or more thicknesses of material must be stitched, which has heretofore offered great difficulties. The same obstacles have been presented in connection with the stitching of the skirts to the waist portions of house dresses and applying a band at the same time, especially where a cluster of the ruffles is necessary at certain parts of the garment, and also the stitching of cuffs to working shirts and the like.

In the drawings accompanying and forming part of the specification, Figure 1 is a rear view of a Metropolitan sewing machine having a top and bottom rotary shaft with my improvement applied thereto; Fig. 2 is an end view of the right-hand end of the machine shown in Fig. 1, showing the details of the top feed and ruffling mechanism; Fig. 3 is a detail perspective view of the ruffling blade and its actuating means; Fig. 4 is a front view of the right-hand end of the machine shown in Fig. 1, or looking in the direction of the arrow in Fig. 2; Fig. 5 is a rear end or left-hand view of Fig. 1, looking in the direction of the arrow in said Fig. 1; Fig. 6 is a detail perspective view of the top feed dog and its holding means; and Fig. 7 is a perspective detail view of the presser foot, showing the feed slots for the top pull feed.

Similar characters of reference indicate corresponding parts in the several figures of the drawings.

The stitching and bottom feed mechanisms may be the same as those generally used in Metropolitan sewing machines and are well known in the art, and therefore need not be herein described at length.

The machine base 1 carries the bottom rotary shaft 2, on which are mounted the combined belt and hand wheel 3 and the vertical arm 4 in which the connections operate between the bottom shaft and the top shaft 5 located in the overhanging arm 6. This top shaft 5 rotates in the usual bearings 7 and

has secured to its end a crank disk 8, (see Fig. 3), carrying a needle driving crank 9 connected with a pitman 10, (see Fig. 2), the lower end of which is connected as at 11 to the needle bar 12 to reciprocate the same in its bearing 13 carried by the machine head 14. A suitable needle holder 15 is secured to the end of this needle bar and carries the needles 16. A thread take-up rod 10 or extension 17 is connected with the needle bar, as at 10', and reciprocates therewith. The bottom shaft 2 endwise reciprocates a looper shaft 18 located in parallelism therewith through bevel gear connection 19, while 15 this looper shaft is rocked by an eccentric connection 20 also carried by the shaft 2. The other end of this eccentric connection 20 is connected for movement to the looper shaft crank 21, (see Fig. 4), so that the 20 looper holders 23 carrying the loopers 24 have a four-motion movement co-operating with the needles to make a double chain-stitch. The looper shaft 18 operates in bearings 25, while the crank shaft 26, with which 25 the bevel gears 19 are connected, operates in bearings 27, one only of which is in sight, and by reason of a fork 28 engaging with this crank shaft 26 the looper shaft 18 is endwise reciprocated. A cloth plate 29 supports the work and also a hemmer attachment 30, which is raised slightly from the plate to permit one portion of the goods to be fed thereunder, while a strip folder 32, which is also secured at 33 to this cloth or 35 slide plate, guides the strip to the stitching mechanism to be stitched to the bottom of the work.

The presser foot 34, (see Fig. 7), is cut out as at 35 and has ears 36 to assist in 40 guiding the work. The foot also has vertically extending lugs 37 provided with holes 38 for securing it to its shank 39, (see Fig. 2). This shank is pivotally secured to the presser bar 40, which slides in a bushing 41, 45 which is secured to the machine head 14. A presser bar guide 42 is secured to the presser bar, as at 43, to prevent axial movement of the same, and it also provides a means for lifting the presser bar through 50 the aid of a hand lifter 44 operating thereunder and through the aid of a vertical angle rod 45 extending upward from said guide which coacts with a foot lifter lever 46. This lever 46 is pivoted at 47, (see Fig. 55 1), to the overhanging arm 6, and is operated by a rod 48 extending down to and connected with a foot treadle, (not shown). A spring and collar 49 holds the parts in normal position when not in use. The presser 60 foot 34 is slotted, as at 50, to receive the top feed dogs 51, which are provided with teeth and vertical walls 52 having pin holes 53 to receive pivot pins 54 for pivotally securing them to their shanks. Each of these 65 shanks has a vertical stem 57 adjustably se-

cured to a plate 58. This plate terminates in an offset extension 59 adjustably secured to a top feed bar 60, as at 61. This top feed bar is pivotally connected at 62 with a lever 63, which in turn is secured to a rock shaft 70 64. This rock shaft extends along the back of the machine and operates in bearings 66, one at each end, and is actuated by a curved arm 67 secured to the shaft, as at 68. A slide block 69 is mounted and may be 75 shifted on this curved arm 67. This slide block has pivotally secured thereto an arm 71 reaching over and connecting with an adjustable crank 73 carried by a disk 74, which may be part of the top shaft 5. The 80 top feed bar 60 is shown as a three-armed member, with its third end pivotally connected to a vertical link 76 extending upward through a slot in the head back of the presser bar bushing 41, (see Figs. 2 and 4), 85 with its upper end pivotally connected to a pin 79 for swinging movement. This pin 79 operates vertically in a slot 80 of a yoke 81, which is secured to the presser bar 40 for movement therewith, so that when the presser 90 bar is lifted it will lift this pin and the parts connected therewith, to wit the links 76 and 96, and thereby the top feed and ruffler. A presser bar spring 82 has one end resting on top of the presser bar and its other end 95 83 resting on a lug carried by the top arm 6, a pressure regulating screw 84, (see Fig. 1), being provided to adjust the pressure of the presser foot on the work. The needle bar driving crank 9 has an arm 85 which 100 carries a crank pin 86 projecting into a lug 87 shown as a part of a barrel 88 in which a spring 89 is located, (see dotted lines, Fig. 3), and this spring co-acts with a plunger or piston 90 to give downward pressure to 105 the top feed and ruffler blade. A pin 91 is carried by the plunger and projects into a slot 92 to limit movement of the plunger, which has a vertically extending stem 93 carrying a nut 94. This plunger is provided 110 with a slotted end 95, (see Fig. 3), which carries the pin 79 hereinbefore referred to and which pin co-operates with the yoke 81 secured to the presser bar 40, and this slotted end receives a swinging arm 96, which is 115 also pivotally secured therein by said pin 79 so as to swing. This swinging arm has a yoke 97 adjustably secured to its lower end for adjustably supporting a ruffler blade and its bar 98. A link connection 99 couples this 120 swinging arm 96 with a rocker arm 100, (see Figs. 2, 3 and 5), for in and out movements. This arm 100 is secured at its upper end to a rock shaft 102 which rocks in suitable bearings 103. This rock shaft 102 extends 125 along the front side of the overhanging arm 6 substantially opposite the rock shaft 64 at the rear side thereof, and is provided at its opposite end with a curved arm 104 having a slide block 105 mounted thereon and 130

to which is pivotally connected an arm 107 connected with the adjustable crank 73 of the disk 74. Coiled springs 108 and 110 connect the arms 71 and 107 with a post 109 and normally hold the slide blocks 69 and 105 against stops 111 carried by the arms 67 and 104. Duplicate rods 112 are provided for shifting the blocks 69 and 105 on the curved arms as desired, and a connection 113 couples the bottom ends of these rods 112 so that both may be operated at the same time by the chain 114 connected with a foot treadle 115, (see Fig. 5), or this connection 113 may be omitted and the chain 114 connected with either of the rods 112 if desired, and a knee shift used to operate the other rod 112, as the case may be. Adjustable stops 116 are secured in extending portions 117 of the rock shaft bearings 66 and 103, with screws 118 to clamp the same in position, and the right-angle portions 119 of these stops provide means for limiting the downward movement of the blocks 69 and 105. By adjusting the stops 116 to different positions as, for instance, one lower than the other, the bar 113 will assume an angular position to meet such adjustments, thus permitting different or independent differential control of the top feeding instrumentalities. From the foregoing it will be seen that I have provided a new combination of feeding elements which have broad adaptability in view of the fact that a feed dog may be substituted in place of the ruffling blade 98, so that a push and pull feed in connection with the bottom feed can be used, making it possible to feed over any irregularity of seam and bunches etc. in the work without difficulty. On the other hand, cluster ruffles of bulky material present great difficulty in feeding, and this improved feed overcomes this. It also overcomes stretching of the work, as there need be very little pressure on the presser foot and the top and bottom plies of work may be brought out evenly, or for special kinds of work the stroke of the ruffling blade and the top feed may be such as to cause the top ply to come out uneven with the bottom ply. The top feed and ruffling mechanisms are of the differential class, as one may have a different movement from the other, although operated by the same means. The shifting of the crank 73 to and from the center varies the throw of both the top feed and ruffler, while the shifting of the blocks 69 and 105 along the curved arms 67 and 114 give a range of adjustment to meet other conditions. In other words if the sliding blocks 69 and 105 are pulled downward, the movement of the instrumentalities is increased, that is, they move to a greater extent. If the slide blocks are forced to the highest position on the curved arms, the instrumentalities are ineffective on the work in the sense that if the

normal feeding action of the bottom feed is $\frac{1}{16}$ inch per revolution of the machine and the normal action of the instrumentalities is equal to the main feed, then they are practically ineffective because the machine would do the same work without them, but when the slide blocks are brought to a lower position on the curved arms, then their action is increased with respect to the main feed and they become effective on the work. Instantaneous control of these mechanisms may be effected by a simple movement of the operator's foot or a shifting movement of the knee, affording a very flexible control.

The lifting motion of the top feed and ruffler effected by the crank pin 86 enables the feed and ruffler to step over seams or other raised uneven portions of the goods and eliminates back drag, so that the stripper blades usually employed on ruffling machines are unnecessary. This is an important feature because they are usually in the way of the attachments and interfere with the rapid handling of the work and also exert friction on the feeding of the material.

It will, of course, be understood that the various details may be more or less changed without departing from the spirit or scope of this improvement.

I claim as my invention:

1. In a sewing machine, the combination of a pair of instrumentalities for engaging the top of the work, one operative to pull and the other to push the work relatively to the needle, and means for imparting a four-motion movement to each of said instrumentalities and including independent means one for each of said instrumentalities for imparting a part of said four-motion movement.

2. In a sewing machine, the combination of a pair of instrumentalities for engaging the top of the work, one operative to pull and the other to push the work relatively to the needle and each supported for back and forth movement whereby either of said instrumentalities may have a different back and forth movement from that of the other, and means for imparting a four-motion movement to each of said instrumentalities, one of said instrumentalities consisting of a feeding device and the other a ruffling device.

3. In a sewing machine, the combination of a pair of instrumentalities for engaging the top of the work, one operative to pull and the other to push the work relatively to the needle, and means for imparting a four-motion movement to each of said instrumentalities and including independent means for varying the movement of each of said instrumentalities.

4. In a sewing machine, the combination of a pair of instrumentalities for engaging

70

the top of the work, one operative to pull and the other to push the work relatively to the needle and each supported for back and forth movement whereby either of said instrumentalities may have a different back and forth movement from that of the other, and means for imparting a four-motion movement to each of said instrumentalities and including means for changing the movement of both of said instrumentalities, one of said instrumentalities consisting of a feeding device and the other a ruffling device.

5. In a sewing machine, the combination of a pair of instrumentalities for engaging the top of the work, one operative to pull and the other to push the work relatively to the needle, and means for imparting a four-motion movement to each of said instrumentalities and including means under the control of the operator during the operation of the machine for varying the movement of either of said instrumentalities independently of the other whereby they may have a differential movement.

6. In a sewing machine, the combination of a pair of instrumentalities for engaging the top of the work, one operative to pull and the other to push the work relatively to the needle, and means for imparting a four-motion movement to each of said instrumentalities and including means for varying the movement of either of said instrumentalities independently of the other whereby they may have a differential movement, one of said instrumentalities consisting of a feeding device and the other a ruffling device.

7. In a sewing machine, the combination of a pair of instrumentalities for engaging the top of the work, one operative to pull and the other to push the work relatively to the needle, and means for imparting a four-motion movement to each of said instrumentalities and including means for changing the movement of each of said instrumentalities and independent means for varying the movement of each of said instrumentalities whereby they may have a differential movement.

8. In a sewing machine, the combination of a pair of instrumentalities for engaging the top of the work, one operative to pull and the other to push the work relatively to the needle, and means for imparting a four-motion movement to each of said instrumentalities and including means for changing the movement of each of said instrumentalities and means for varying the movement of either of said instrumentalities independently of the other whereby they may have a differential movement, one of said instrumentalities consisting of a feeding device and the other a ruffling device.

9. In a sewing machine, the combination of a top shaft, a pair of instrumentalities for

engaging the top of the work, one operative to pull and the other to push the work relatively to the needle, means connected with said top shaft for imparting a four-motion movement to each of said instrumentalities, 70 a presser-foot bar, means for lifting it, and means connected therewith and with said instrumentality-actuating means whereby on the lifting of said presser-foot bar both of said instrumentalities may be lifted 75 simultaneously.

10. In a sewing machine, the combination of a pair of instrumentalities for engaging the top of the work, one operative to pull and the other to push the work relatively to the needle and each supported for back and forth movement whereby either of said instrumentalities may have a different back and forth movement from that of the other, means for imparting a four-motion movement to each of said instrumentalities, one of said instrumentalities consisting of a feeding device and the other a ruffling device, a presser-foot bar, means for lifting it, and means connected therewith and with 85 said instrumentality-actuating means whereby on the lifting of said presser-foot bar both of said instrumentalities may be lifted 90 simultaneously.

11. In a sewing machine, the combination of a pair of instrumentalities for engaging the top of the work, one operative to pull and the other to push the work relatively to the needle, means for imparting a four-motion movement to each of said instrumentalities and including means for independently varying the movement of each of said instrumentalities, a presser-foot bar, means for lifting it, and means connected therewith and with said instrumentality-actuating 105 means whereby on the lifting of said presser-foot bar both of said instrumentalities may be lifted simultaneously.

12. In a sewing machine, the combination of a pair of instrumentalities for engaging the top of the work, one operative to pull and the other to push the work relatively to the needle, means for imparting a four-motion movement to each of said instrumentalities and including means under the control 110 of the operator during the operation of the machine for varying the movement of either of said instrumentalities independently of the other whereby they may have a differential movement, a presser-foot bar, means for lifting it, and means connected therewith and with said instrumentality-actuating means whereby on the lifting of said presser-foot bar both of said instrumentalities may be lifted 115 simultaneously.

13. In a sewing machine, the combination of a pair of instrumentalities for engaging the top of the work, one operative to pull and the other to push the work relatively to the needle, means for imparting a four- 120 125 130

motion movement to each of said instrumentalities and including means for changing the movement of each of said instrumentalities and means for varying the movement 5 of either of said instrumentalities independently of the other whereby they may have a differential movement, one of said instrumentalities consisting of a feeding device and the other a ruffling device, a presser-foot bar, means for lifting it, and means connected therewith and with said instrumentality-actuating means whereby on the lifting of said presser-foot bar both of said instrumentalities may be lifted simultaneously.

14. In a sewing machine, the combination of a top driving shaft, a pair of rock shafts, a pair of instrumentalities for engaging the top of the work, and means connecting them 20 with the top and rock shafts for imparting a four-motion movement to each of said instrumentalities.

15. In a sewing machine, the combination of a top driving shaft, a pair of rock shafts, 25 a pair of instrumentalities for engaging the top of the work, and means connecting them with the top and rock shafts for imparting a four-motion movement to each of said instrumentalities and including means for 30 changing the movement of both of said instrumentalities.

16. In a sewing machine, the combination of a top driving shaft, a pair of rock shafts, a pair of instrumentalities for engaging the 35 top of the work, and means connecting them with the top and rock shafts for imparting a four-motion movement to each of said instrumentalities and including means for varying the movement of either or both of 40 said instrumentalities thereby to impart a differential movement thereto.

17. In a sewing machine, the combination of a top driving shaft, a pair of rock shafts, a pair of instrumentalities for engaging the 45 top of the work, and means connecting them with the top and rock shafts for imparting a four-motion movement to each of said instrumentalities and including means for changing the movement of both of said instrumentalities and means for varying the 50 movement of either or both of said instrumentalities thereby to impart a differential movement thereto.

18. In a sewing machine, the combination 55 of a top driving shaft, a pair of rock shafts, a pair of instrumentalities for engaging the top of the work, means connecting them with the top and rock shafts for imparting a four-motion movement to each of said instrumentalities, a presser-foot bar, and means connecting said bar with a part of said actuating means whereby on manipulating said presser-foot bar said instrumentalities may be raised or lowered.

65 19. In a sewing machine, the combination

of a top driving shaft, a pair of rock shafts, a pair of instrumentalities for engaging the top of the work, means connecting them with the top and rock shafts for imparting a four-motion movement to each of said instrumentalities and including means for changing the movement of both of said instrumentalities, a presser-foot bar, and means connecting said bar with a part of said actuating means whereby on manipulating said presser-foot bar said instrumentalities may be raised or lowered. 70

20. In a sewing machine, the combination of a top driving shaft, a pair of rock shafts, a pair of instrumentalities for engaging the top of the work, means connecting them with the top and rock shafts for imparting a four-motion movement to each of said instrumentalities and including means for varying the movement of either or both of said instrumentalities thereby to impart a differential movement thereto, a presser-foot bar, and means connecting said bar with a part of said actuating means whereby on manipulating said presser-foot bar said instrumentalities may be raised or lowered. 80

21. In a sewing machine, the combination of a bottom feed, a top feed located to act at the rear of the needle, a top ruffling mechanism located to act on the material in front of the needle, means for operating said top feed and ruffling mechanism and including means for imparting a differential movement thereto, means under the control of the operator during the operation of the machine, for adjusting said operating means. 95

22. In a sewing machine, the combination of a bottom feed, a top feed located to act at the rear of the needle, a top ruffling mechanism located to act on the material in front of the needle, means for operating said top feed and ruffling mechanism and including means for imparting a differential movement thereto and also including means for changing the movement thereof, means under the control of the operator during the operation of the machine, for adjusting said operating means. 105

23. In a sewing machine, the combination of a top driving shaft, a pair of rock shafts, a pair of instrumentalities for engaging the top of the work, one comprising a feeding device and the other a ruffling device, and means connecting them with the top and rock shafts for imparting a four-motion movement to each of said instrumentalities. 110

24. In a sewing machine, the combination of a top driving shaft, a pair of rock shafts, a pair of instrumentalities for engaging the top of the work, one comprising a feeding device and the other a ruffling device, and means connecting them with the top and rock shafts for imparting a four-motion 125

130

movement to each of said instrumentalities and including means for varying the movement of either or both of said instrumentalities whereby they may have a differential 5 movement.

25. In a sewing machine, the combination of a top driving shaft, a bottom driving shaft, a bottom feed, a pair of rock shafts, a top feeding instrumentality located to act 10 at the rear of the needle, an instrumentality located to act in front of the needle to push the material, and means connecting them with the top and rock shafts for imparting a four-motion movement to each thereof and 15 including means for varying the movement of either of said instrumentalities whereby they may have a differential movement.

26. In a sewing machine, the combination of a top driving shaft, a bottom driving 20 shaft, a bottom feed, a pair of rock shafts, a top feeding instrumentality located to act at the rear of the needle, an instrumentality located to act in front of the needle to push the material, and means connecting them 25 with the top and rock shafts for imparting a four-motion movement to each thereof and including means for varying the movement of either of said instrumentalities whereby they may have a differential movement 30 and means for changing the movement of both of said instrumentalities.

27. In a sewing machine, the combination of a top driving shaft, a bottom driving shaft, a bottom feed, a pair of rock shafts, 35 a top feeding instrumentality located to act at the rear of the needle, an instrumentality located to act in front of the needle to push the material, means connecting them with the top and rock shafts for imparting a four-motion movement to each thereof and 40 including means for varying the movement of either of said instrumentalities whereby they may have a differential movement and means for changing the movement of both 45 of said instrumentalities, a presser-foot bar, and means connecting it with a part of the actuating means of said instrumentalities whereby on the lifting of said presser-foot bar both of said instrumentalities may be 50 raised.

28. In a sewing machine, the combination of a pair of instrumentalities for engaging the top of the work, one operative to pull and the other to push the work relatively to 55 the needle, means for imparting a four-motion movement to each of said instrumentalities, and means under the control of the operator for rendering said instrumentalities effective or ineffective either independently 60 of the other.

29. In a sewing machine, the combination of a pair of instrumentalities for engaging the top of the work, one operative to pull and the other to push the work relatively 65 to the needle, means for imparting a four-

motion movement to each of said instrumentalities, one of said instrumentalities consisting of a feeding device and the other a ruffling device, and means under the control of the operator for rendering said instrumentalities effective or ineffective either independently of the other. 70

30. In a sewing machine, the combination of a pair of instrumentalities for engaging the top of the work, one operative to pull 75 and the other to push the work relatively to the needle, means for imparting a four-motion movement to each of said instrumentalities and including means for changing the movement of both of said instrumentalities, and means under the control of the operator for rendering said instrumentalities effective or ineffective either independently of the other. 80

31. In a sewing machine, the combination 85 of a pair of instrumentalities for engaging the top of the work, one operative to pull and the other to push the work relatively to the needle, means for imparting a four-motion movement to each of said instrumentalities and including means for varying the movement of either of said instrumentalities whereby they may have a differential movement, and means under the control 90 of the operator for rendering said instrumentalities effective or ineffective. 95

32. In a sewing machine, the combination of a pair of instrumentalities for engaging the top of the work, one operative to pull and the other to push the work relatively to 100 the needle, means for imparting a four-motion movement to each of said instrumentalities and including means for changing the movement of each of said instrumentalities and means for varying the movement of each of said instrumentalities whereby they may have a differential movement, and means under the control of the operator for rendering said instrumentalities effective or ineffective. 105

33. In a sewing machine, the combination of a top driving shaft, a pair of rock shafts, a pair of instrumentalities for engaging the top of the work, means connecting them with the top and rock shafts for imparting 110 a four-motion movement to each of said instrumentalities, and means under the control of the operator for rendering said instrumentalities effective or ineffective. 115

34. In a sewing machine, the combination 120 of a top driving shaft, a pair of rock shafts, a pair of instrumentalities for engaging the top of the work, means connecting them with the top and rock shafts for imparting a four-motion movement to each of said instrumentalities and including means for changing the movement of both of said instrumentalities, and means under the control of the operator for rendering said instrumentalities effective or ineffective. 125

35. In a sewing machine, the combination of a top driving shaft, a pair of rock shafts, a pair of instrumentalities for engaging the top of the work, means connecting them with the top and rock shafts for imparting a four-motion movement to each of said instrumentalities and including means for varying the movement of either or both of said instrumentalities thereby to impart a differential movement thereto, and means under the control of the operator for rendering said instrumentalities effective or ineffective.

36. In a sewing machine, the combination of a top driving shaft, a pair of rock shafts, a pair of instrumentalities for engaging the top of the work, means connecting them with the top and rock shafts for imparting a four-motion movement to each of said instrumentalities and including means for changing the movement of both of said instrumentalities and means for varying the movement of either or both of said instrumentalities thereby to impart a differential movement thereto, and means under the control of the operator for rendering said instrumentalities effective or ineffective.

37. In a sewing machine, the combination of a top driving shaft, a pair of rock shafts, a pair of instrumentalities for engaging the top of the work, means connecting them with the top and rock shafts for imparting a four-motion movement to each of said instrumentalities, a presser-foot bar, means connecting said bar with a part of said actuating means whereby on manipulating said presser-foot bar said instrumentalities may be raised or lowered, and means under the control of the operator for rendering said instrumentalities effective or ineffective.

38. In a sewing machine, the combination of a pair of instrumentalities for engaging the top of the work, one comprising a feeding device and one projecting toward the other and located one in front of and the other in the rear of the needle, a top driving shaft, means connected therewith and with said instrumentalities for imparting a rising and falling movement thereto, and independent means also connected with said shaft for imparting a to and fro movement to both of said instrumentalities.

39. In a sewing machine, the combination of a pair of instrumentalities for engaging the top of the work, one comprising a feeding device, a driving shaft, means connected therewith and with said instrumentalities for imparting a rising and falling movement thereto, and means for imparting a to-and-fro movement thereto, said first means including a spring-pressed piston crank connected with said driving shaft.

40. In a sewing machine, the combination of a pair of instrumentalities for engaging the top of the work, one comprising a feed-

ing device, a driving shaft, means connected therewith and with said instrumentalities for imparting a rising and falling movement thereto, means for imparting a to-and-fro movement thereto, said first means including a spring-pressed piston crank connected with said driving shaft, a presser-foot bar, and means connecting it with a part of said piston whereby on the lifting of said presser-foot bar said piston will be lifted.

41. In a sewing machine, the combination of a pair of instrumentalities for engaging the top of the work, one comprising a feeding device, a driving shaft, means connected therewith and with said instrumentalities for imparting a rising and falling movement thereto, means for imparting a to-and-fro movement thereto, said first means including a spring-pressed piston, a presser-foot bar, means connecting it with a part of said piston whereby on the lifting of said presser-foot bar said piston will be lifted, and means under the control of the operator for rendering said instrumentalities effective or ineffective.

42. In a sewing machine, the combination of a pair of instrumentalities for engaging the top of the work, one comprising a feeding device, a driving shaft, means connecting said instrumentalities with said driving shaft for operating them, a pair of rock shafts, means connecting said instrumentalities with said rock shafts, and means connecting said rock shafts with said driving shaft for operating said rock shafts.

43. In a sewing machine, the combination of a pair of instrumentalities for engaging the top of the work, one comprising a feeding device, a driving shaft, means connecting said instrumentalities with said driving shaft for operating them, a pair of rock shafts, means connecting said instrumentalities with said rock shafts, and adjustable means connecting said rock shafts with said driving shaft for operating said rock shafts.

44. In a sewing machine, the combination of a pair of instrumentalities for engaging the top of the work, one comprising a feeding device, a driving shaft, means connecting said instrumentalities with said driving shaft for operating them, a pair of rock shafts, means connecting said instrumentalities with said rock shafts, and sliding means connecting said rock shafts with said driving shaft for operating said rock shafts.

45. In a sewing machine, the combination of a pair of instrumentalities for engaging the top of the work, one comprising a feeding device, a driving shaft, means connecting said instrumentalities with said driving shaft for operating them and including a spring-pressed piston, a pair of rock shafts, means connecting said instrumentalities with said rock shafts, and sliding means connect-

ing said rock shafts with said driving shaft for operating said rock shafts.

111 operating said rock shafts.

46. In a sewing machine, the combination of a pair of instrumentalities for engaging the top of the work, one comprising a feeding device, a driving shaft, means connecting said instrumentalities with said driving shaft for operating them, a pair of rock shafts, means connecting said instrumentalities with said rock shafts, a pair of curved arms connected with said rock shafts, a sliding block located on each of said arms, a crank disk connected with said driving shaft, and a pair of connections between said sliding blocks and said crank disk.

47. In a sewing machine, the combination of a pair of instrumentalities for engaging the top of the work, one comprising a feeding device, a driving shaft, means connecting said instrumentalities with said driving shaft for operating them, a pair of rock shafts, means connecting said instrumentalities with said rock shafts, a pair of curved arms connected with said rock shafts, a sliding block located on each of said arms, a crank disk connected with said driving shaft, a pair of connections between said sliding blocks and said crank disk, and means connected with said blocks for shifting said arms thereby to render the said instrumentalities effective or ineffective.

35 48. In a sewing machine, the combination of a pair of instrumentalities for engaging the top of the work, one comprising a feeding device, a driving shaft, means connecting said instrumentalities with said driving shaft for operating them, a pair of rock shafts, means connecting said instrumentalities with said rock shafts, a pair of curved arms connected with said rock shafts, a sliding block located on each of said arms, a crank disk connected with said driving shaft, a pair of connections between said sliding blocks and said crank disk, and adjustable means for limiting the movement of said sliding blocks.

40 45

49. In a sewing machine, the combination of a pair of instrumentalities for engaging the top of the work, one comprising a feeding device, a driving shaft, means connecting said instrumentalities with said driving shaft for operating them, a pair of rock shafts, means connecting said instrumentalities with said rock shafts, a pair of curved arms connected with said rock shafts, a sliding block located on each of said arms, a crank disk connected with said driving shaft, a pair of connections between said sliding blocks and said crank disk, adjustable means for limiting the movement of said sliding blocks, and stops for said sliding blocks.

50. In a sewing machine, the combination of a pair of instrumentalities for engaging the top of the work, one comprising a feed-
65 ing device, a driving shaft, means connect-

ing said instrumentalities with said driving shaft for operating them, a pair of rock shafts, means connecting said instrumentalities with said rock shafts, a pair of curved arms connected with said rock shafts, a sliding block located on each of said arms, a crank disk connected with said driving shaft, a pair of connections between said sliding blocks and said crank disk, adjustable means for limiting the movement of said sliding blocks, stops for said sliding blocks, and springs for holding said connections in engagement with said stops. 70 75

51. In a sewing machine, the combination of a pair of instrumentalities for engaging the top of the work, one comprising a feeding device, a driving shaft, means connecting said instrumentalities with said driving shaft for operating them, a pair of rock shafts, means connecting said instrumentalities with said rock shafts, a pair of curved arms connected with said rock shafts, a sliding block located on each of said arms, a crank disk connected with said driving shaft, a pair of connections between said sliding blocks and said crank disk, adjustable means for limiting the movement of said sliding blocks, stops for said sliding blocks, springs for holding said connections in engagement with said stops, and means connected with said sliding blocks for rendering said instrumentalities effective or ineffective. 80 85 90 95

52. In a sewing machine, the combination of a pair of instrumentalities for engaging the top of the work, one comprising a feeding device, a driving shaft, means connecting said instrumentalities with said driving shaft for operating them and including a spring-pressed piston, a pair of rock shafts, means connecting said instrumentalities with said rock shafts, a pair of curved arms connected with said rock shafts, a sliding block located on each of said arms, a crank disk connected with said driving shaft, a pair of connections between said sliding blocks and said crank disk, adjustable means for limiting the movement of said sliding blocks, stops for said sliding blocks, springs for holding said connections in engagement with said stops, and means connected with said sliding blocks for rendering said instrumentalities effective or ineffective. 100
105
110
115

53. In a sewing machine, the combination of a pair of instrumentalities for engaging the top of the work, one comprising a feeding device, a driving shaft, means connecting said instrumentalities with said driving shaft for operating them and including a spring-pressed piston, a pair of rock shafts, means connecting said instrumentalities with said rock shafts, a pair of curved arms connected with said rock shafts, a sliding block located on each of said arms, a crank disk connected with said driving shaft, a pair 130

of connections between said sliding blocks and said crank disk, adjustable means for limiting the movement of said sliding blocks, stops for said sliding blocks, springs 5 for holding said connections in engagement with said stops, means connected with said sliding blocks for rendering said instrumentalities effective or ineffective, a presser-foot bar, and means connecting it with said 10 spring-pressed piston whereby on the lifting of said bar said instrumentalities will be raised.

54. In a sewing machine, the combination of a pair of instrumentalities for engaging 15 the top of the work, one comprising a feeding device and the other a ruffling device, a top driving shaft, means connecting said instrumentalities with said top driving shaft for operating them and including a spring- 20 pressed piston, a pair of rock shafts one located at each side of the top driving shaft, means connecting said instrumentalities with said rock shafts, a pair of curved arms connected with said rock shafts, a pair of sliding 25 blocks on said arms, means connected with said blocks and under the control of the operator for rendering said instrumentalities effective or ineffective, a crank disk carried by said top shaft, and a pair of connections 30 adjustably connected with said disk and with said blocks.

55. In a sewing machine, the combination of a pair of instrumentalities for engaging the top of the work, one comprising a feeding 35 device and the other a ruffling device, a top driving shaft, means connecting said instrumentalities with said top driving shaft for operating them and including a spring-pressed piston, a pair of rock shafts one 40 located at each side of the top driving shaft, means connecting said instrumentalities with said rock shafts, a pair of curved arms connected with said rock shafts, a pair of sliding blocks on said arms, means connected 45 with said blocks and under the control of the operator for rendering said instrumentalities effective or ineffective, a crank disk carried by said top shaft, a pair of connections 50 adjustably connected with said disk and with said blocks, and means for limiting the movement of said blocks on said arms.

56. In a sewing machine, the combination of a pair of instrumentalities for engaging 55 the top of the work, one comprising a feeding device, a top driving shaft, means connecting said instrumentalities with said shaft for imparting a rising and falling movement to said instrumentalities, a pair of rock 60 shafts, means connecting said rock shafts with said instrumentalities, and means adjustably connecting said rock shafts with said driving shaft for rocking said shafts and thereby imparting a to-and-fro movement 65 to said instrumentalities and including

a pair of sliding blocks adjustable to vary the to-and-fro movement of said instrumentalities.

57. In a sewing machine, the combination of a pair of instrumentalities for engaging 70 the top of the work, one comprising a feeding device, a top driving shaft, means connecting said instrumentalities with said shaft for imparting a rising and falling movement to said instrumentalities, a pair of rock 75 shafts, means connecting said rock shafts with said instrumentalities, means adjustably connecting said rock shafts with said driving shaft for rocking said shafts and thereby imparting a to-and-fro movement to 80 said instrumentalities and including a pair of sliding blocks adjustable to vary the to-and-fro movement of said instrumentalities, and means connected with said rock shaft actuating means for rendering said instrumentalities effective or ineffective. 85

58. In a sewing machine, the combination of a pair of instrumentalities for engaging the top of the work, one comprising a feeding device, a top driving shaft, means connecting said instrumentalities with said shaft for imparting a rising and falling movement to said instrumentalities, a pair of rock 90 shafts, means connecting said rock shafts with said instrumentalities, means adjustably connecting said rock shafts with said driving shaft for rocking said shafts and thereby imparting a to-and-fro movement to 95 said instrumentalities and including a pair of sliding blocks adjustable to vary the to-and-fro movement of said instrumentalities, means connected with said rock shaft actuating means for rendering said instrumentalities effective or ineffective, and a presser-foot bar connected with the means for imparting a rising and falling movement to 100 said instrumentalities whereby on the lifting of said presser-foot bar said instrumentalities may be lifted. 105

59. In a sewing machine, the combination 110 of a combined top feed and ruffling mechanism, each supported to have a four-motion movement, and means for imparting it and including a pair of duplicate means for imparting the to-and-fro movement thereof. 115

60. In a sewing machine, the combination of a combined top feed and ruffling mechanism, each supported to have a four-motion movement, means for imparting the rising and falling movement thereof, and duplicate 120 means for imparting the to-and-fro movement thereof. 125

61. In a sewing machine, the combination of a combined top feed and ruffling mechanism, each supported to have a four-motion movement, means for imparting the rising and falling movement thereof, and duplicate means for imparting the to-and-fro movement thereof and including means for varying such to-and-fro movement. 130

62. In a sewing machine, the combination of a combined top feed and ruffling mechanism, each supported to have a four-motion movement, means for imparting the rising and falling movement thereof, and duplicate means for imparting the to-and-fro movement thereof and including means for varying such to-and-fro movement and means for changing equally the movement of both of 10 said instrumentalities.

63. In a sewing machine, the combination of a combined top feed and ruffling mechanism, each supported to have a four-motion movement, means for imparting the rising and falling movement thereof, duplicate means for imparting the to-and-fro movement thereof and including means for varying such to-and-fro movement, and means under the control of the operator for rendering said instrumentalities effective or ineffective. 15

64. In a sewing machine, the combination of a combined top feed and ruffling mechanism, each supported to have a four-motion movement, means for imparting the rising and falling movement thereof, duplicate means for imparting the to-and-fro movement thereof and including means for varying such to-and-fro movement, means 20 under the control of the operator for rendering said instrumentalities effective or ineffective and means for independently lifting said instrumentalities out of operation.

65. In a sewing machine, the combination of feeding mechanism comprising a feed dog, a three-armed lever connected therewith, a rock shaft connected with one arm of said lever, a top driving shaft, means connecting said rock shaft with said top 35 driving shaft, and means connecting said top shaft with another arm of said lever.

66. In a sewing machine, the combination of feeding mechanism comprising a feed dog, a three-armed lever connected therewith, a rock shaft connected with one arm of said lever, a top driving shaft, means connecting said rock shaft with said top driving shaft, and means connecting said top shaft with another arm of said lever 40 and including a spring-pressed piston.

67. In a sewing machine, the combination of feeding mechanism comprising a feed dog, a three-armed lever connected therewith, a rock shaft connected with one arm of said lever, a top driving shaft, means connecting said rock shaft with said top driving shaft, means connecting said top shaft with another arm of said lever and including a spring-pressed piston, a presser-foot 55 bar, and means connecting said piston with said presser-foot bar.

68. In a sewing machine, the combination of a top driving shaft, a piston casing having a crank connection with said driving

shaft, a spring-pressed piston in said casing, 65 a pair of instrumentalities for engaging the top of the work, a member pivotally connected with said piston and with one of said instrumentalities, a three-armed lever having one arm connected with the other of said instrumentalities and an arm pivotally connected with said piston, a pair of rock shafts one connected with the third arm of said lever and the other connected with said first member, and means connected with said top 70 driving shaft for rocking said rock shafts. 75

69. In a sewing machine, the combination of a top driving shaft, a piston casing having a crank connection with said driving shaft, a spring-pressed piston in said casing, 80 a pair of instrumentalities for engaging the top of the work, a member pivotally connected with said piston and with one of said instrumentalities, a three-armed lever having one arm connected with the other of said instrumentalities and an arm pivotally connected with said piston, a pair of rock shafts one connected with the third arm of said lever and the other connected with said first member, and means connected with said top driving shaft for rocking said rock shafts and including a pair of sliding members and means for limiting the movement thereof. 85

70. In a sewing machine, the combination of a top driving shaft, a piston casing having a crank connection with said driving shaft, a spring-pressed piston in said casing, 90 a pair of instrumentalities for engaging the top of the work, a member pivotally connected with said piston and with one of said instrumentalities, a three-armed lever having one arm connected with the other of said instrumentalities and an arm pivotally connected with said piston, a pair of rock shafts one connected with the third arm of said lever and the other connected with said first member, and means connected with said top driving shaft for rocking said rock shafts and including a pair of sliding members and means for limiting the movement thereof. 95

71. In a sewing machine, the combination of a pair of work-engaging instrumentalities, a rotary driving shaft, and means connecting each of said instrumentalities with said driving shaft, said means comprising a 100 crank-connected member and a member having a sliding engagement relatively thereto in a substantially vertical line. 110

72. In a sewing machine, the combination of a pair of work-engaging instrumentalities, a driving shaft, and means connecting said instrumentalities with said driving shaft and comprising a crank-connected 115 120 125

member and a spring-pressed member having a sliding engagement relatively thereto in a substantially vertical line.

73. In a sewing machine, the combination 5 of a pair of work-engaging instrumentalities, a driving shaft, means connecting said instrumentalities with said driving shaft and comprising a crank-connected member and a member having a sliding engagement 10 relatively thereto in a substantially vertical line, and means for imparting a to-and-fro movement to each of said instrumentalities.

74. In a sewing machine, the combination 15 of a pair of work-engaging instrumentalities, a driving shaft, means connecting said instrumentalities with said driving shaft and comprising a crank-connected member and a spring-pressed member having a sliding engagement relatively thereto in a sub- 20 stantially vertical line, and means for imparting a to-and-fro movement to each of said instrumentalities.

75. In a sewing machine, the combination 25 of a pair of work-engaging instrumentalities, a driving shaft, means connecting said instrumentalities with said driving shaft and comprising a crank-connected member and a member having a sliding engagement relatively thereto, and means for imparting a 30 to-and-fro movement to each of said instrumentalities, said means comprising a pair of rock shafts having connection with said driving shaft.

76. In a sewing machine, the combination 35 of a pair of work-engaging instrumentalities, a driving shaft, means connecting said instrumentalities with said driving shaft and comprising a crank-connected member and a spring-pressed member having a sliding engagement relatively thereto, and means for imparting a to-and-fro movement to each of said instrumentalities, said means comprising a pair of rock shafts having connection with said driving shaft.

45 77. In a sewing machine, the combination of a pair of work-engaging instrumentalities, a driving shaft, means connecting said instrumentalities with said driving shaft and comprising a crank-connected member 50 and a member having a sliding engagement relatively thereto, means for imparting a to-and-fro movement to each of said instrumentalities, said means comprising a pair of rock shafts having connection with said 55 driving shaft, and means for throwing said instrumentalities into and out of operation.

78. In a sewing machine, the combination 60 of a pair of work-engaging instrumentalities, a driving shaft, means connecting said instrumentalities with said driving shaft and comprising a crank-connected member and a spring-pressed member having a sliding engagement relatively thereto, means for imparting a to-and-fro movement to each

of said instrumentalities, said means comprising a pair of rock shafts having connection with said driving shaft, and means for throwing said instrumentalities into and out of operation.

79. In a sewing machine, the combination 70 of a pair of work-engaging instrumentalities, a driving shaft, means connecting said instrumentalities with said driving shaft and comprising a crank-connected member and a member having a sliding engagement 75 relatively thereto, means for imparting a to-and-fro movement to each of said instrumentalities, said means comprising a pair of rock shafts having connection with said driving shaft, a presser-foot bar, means for 80 lifting it, and means connecting it with the operating means for said instrumentalities whereby on the lifting of the presser-foot bar said instrumentalities will be lifted.

80. In a sewing machine, the combination 85 of a pair of work-engaging instrumentalities, a driving shaft, means connecting said instrumentalities with said driving shaft and comprising a crank-connected member and a spring-pressed member having a sliding engagement relatively thereto, means for imparting a to-and-fro movement to each of said instrumentalities, said means comprising a pair of rock shafts having connection 90 with said driving shaft, a presser-foot bar, means for lifting it, and means connecting it with the operating means for said instrumentalities whereby on the lifting of the presser-foot bar said instrumentalities will 95 be lifted.

81. In a sewing machine, the combination 100 of a top driving shaft, a pair of work-engaging instrumentalities, the same means connecting both of said instrumentalities with said top driving shaft and comprising a crank-connected member and a member 105 having a sliding engagement relatively thereto.

82. In a sewing machine, the combination 110 of a top driving shaft, a pair of work-engaging instrumentalities, the same means connecting both of said instrumentalities with said top driving shaft and comprising a crank-connected member and a member having a sliding engagement relatively 115 thereto, and duplicate means for imparting a to-and-fro movement to each of said instrumentalities.

83. In a sewing machine having a cloth plate, the combination of a top driving shaft, 120 a pair of instrumentalities for engaging the top of the work, one operative at the rear of the needle and the other in the front thereof to insure the feeding of the work, and means located entirely above the cloth 125 plate and connected with said top shaft for imparting a four-motion movement to each of said instrumentalities.

84. In a sewing machine the combination of a pair of instrumentalities for engaging the top of the work, one operative at the rear of the needle and the other in front thereof to assist in the passage of the work relative to the needle, and means for imparting a four-motion movement to each of said

instrumentalities, and including means for varying, one independently of the other, the movement of both said instrumentalities.

10

Signed at Nyack, in the county of Rockland and State of New York, this 17th day of February 1916.

JOHN P. WEIS.
